UNITED STATES PATENT OFFICE.

ERNEST HEINEMANN, OF ALMA, WISCONSIN.

AUTOMATIC LOCK FOR BARN-DOORS.

1,254,905.

Specification of Letters Patent. Patented Jan. 29, 1918.

Application filed November 6, 1916. Serial No. 129,825.

To all whom it may concern:

Be it known that I, ERNEST HEINEMANN, a citizen of the United States, residing at Alma, in the county of Buffalo and State of Wisconsin, have invented certain new and useful Improvements in Automatic Locks for Barn-Doors, of which the following is a specification, reference being had to the accompanying drawings.

10 This invention relates to locks and latches and the general object of the invention is to provide a lock particularly adapted to barn doors and the doors of outhouses, which is so constructed that it will prevent live stock 15 from opening the doors of the barn or outhouse.

A further object of the invention is to provide a lock or latch of this character including an operating spindle which is longitudinally shiftable as well as rotatable, which spindle coacts with a detent when the lock bolt is thrown preventing a retraction of the bolt, the spindle being shiftable, however, longitudinally to disengage it 25 from the detent so that the bolt may be retracted.

Still another object of the invention is to provide a latch or bolt of this character in which the bolt is held in a retracted position 30 by resilient means which will prevent the bolt from being projected accidentally as by live stock but which will permit by a slight effort the detachment of the operating mechanism from the spring actuated means to 35 thus permit the bolt to be thrown.

A further object is to provide a lock or latch of this character which is very simple in construction, may be easily applied and which is thoroughly effective in operation.

40 Other objects will appear in the course of the following description.

My invention is illustrated in the accompanying drawings, wherein—

Figure 1 is a face view of my latching device, the spindle being in section;

Fig. 2 is a sectional view through a door with the locking device applied thereto, the arm 25 and link 26 being partly broken away;

50 Fig. 3 is an end view of the plate 10 with the rod 11; and

Fig. 4 is an end view of the rod 15 detached from the plate 10.

Referring to these drawings, 10 designates 55 the face plate which may be fastened in any suitable manner to a door or like closure,

the face plate being formed with a plurality of transverse ribs 11 formed with guide passages 12 for the passage of a longitudinally shiftable bolt 13. Fastening screws 14 may 60 pass through certain of these ribs to hold the plate to the door. One of these ribs designated 15 is relatively wide and has a relatively long passage 16 for the bolt 13. Passing through the door and through the 65 plate 10, as illustrated in Fig. 2 is a handle spindle or operating spindle 17. This spindle at one end is formed with the integral handle 18 and at its other end is screw threaded for engagement with the nuts 19 70 and 20 and passes through an aperture in a handle 21, the nuts 19 and 20 holding the handle firmly in place so that when the handle is turned the spindle will be turned. The spindle is longitudinally shiftable 75 through an opening 22 formed in the plate 10 and passing through the thickened portion 15, and between the plate 10 and a collar 23 there is disposed a coiled compression spring 24 which urges the spindle in 80 the direction of the arrow, Fig. 2. The spindle 17 at its end adjacent the handle 18 is formed with the radially projecting arm 25 to which is pivotally connected a link 26, this link being slightly curved at its end 85 toward the arm 25, and extending longitudinally across the face of the plate 10 and being pivotally connected at its end to an upwardly turned portion 27 of the bolt 13. It will be seen that a rotation of the spindle 90 17 in a clockwise direction in Fig. 1 will cause the projection of the bolt and that the rotation of the spindle in a counterclockwise direction will cause the retraction of the bolt.

The portion 15 of the plate 10 is formed with the outwardly projecting detent lug 28 which is disposed in the path of movement of the arm 25 when the spring 24 urges said arm inward but by drawing the spindle 100 17 outward the arm 25 will escape the detent lug 28 and the spindle may be rotated to retract the bolt. The bolt 13 is projected by means of the spring 31 which engages against a pin or other abutment 30 105 mounted upon the bolt, the other end of the spring bearing against the rod 11.

The operation of this latch or bolt will be obvious from what has gone before. When the bolt is being retracted the spindle 110 is turned to carry the link 26 and the bolt 13 to its extreme rearward position, a further

movement in the same direction of the spindle shifting the bolt slightly forward and the arm 25 into such position that the arm is in the dotted line position in Fig. 1 and 5 abutted against the inclined face of the thickened portion of the plate 10 and the rib 15, which thickened portion forms a stop limiting any further movement of the arm 25 in a counterclockwise direction and any 10 further projection of the bolt. Under these circumstances a rotation of the spindle in a clockwise direction must first carry the bolt 13 and link 26 rearward and this is resisted by the spring 31. The spindle may however be manually rotated against the force of 15 the spring 31 to shift the bolt rearward to its extreme rear position and then forward to carry the arm 25 into the full line position in Fig. 1, thus projecting the bolt. 20 When it has reached the full line position, the arm 25 will be just beyond the lug 28, which lug has an angularly disposed or inclined face and the spring 24 will draw the spindle inward so as to carry the arm 25 into the plane of the lug 28. Under 25 these circumstances the bolt is projected and cannot be retracted until the spindle has been shifted against the force of the spring 24 to carry the arm 25 out of the plane of 30 the detent lug 28.

A latch of this character it will be seen cannot accidentally be operated by animals because it involves two movements to 35 retract the bolt, not only a movement or rotation, but a longitudinal movement of the spindle against the force of the spring 24. When the bolt is retracted it cannot be accidentally projected because the movement to project the bolt must be against the force 40 of the spring 31.

Having described my invention, what I claim is:

1. In a latch of the character described, a bolt, a spring urging the bolt in one direction to a projected position, an actuating member having limited movement in the arc of a circle and operatively connected to the bolt to shift it in either direction, a movement of said member in one direction shifting the bolt rearward against the action of the spring and then forward with the expansion of the spring upon a further movement of the actuating member in the same direction, and a stop limiting the forward movement of the bolt when the actuating member is rotated in the said direction to thereby prevent the complete projection of the bolt, the actuating member being shiftable in the opposite direction to that first named to shift the bolt rearward against the force of the spring and then permit the spring to fully project the bolt upon a further movement of the actuating member in the same direction.

65 2. In a latch of the character described,

a longitudinally movable bolt, a spindle mounted for rotation and for longitudinal movement at right angles to the plane of the bolt, said spindle having a radially extending arm, a link connecting the bolt to the arm, a spring urging the spindle longitudinally in one direction, and a detent fixed with relation to the spindle with which the arm is adapted to engage when the bolt has been shifted to a projected position and urged in one direction by said spring. 70

3. In a latch of the character described, a supporting base, a bolt longitudinally movable upon the supporting base, a spindle extending through the supporting base and mounted therein for rotation and longitudinal movement, a spring surrounding the spindle and urging the spindle longitudinally in one direction, an arm extending from the spindle, a link connecting the arm to the bolt, a detent lug projecting from the base and disposed in the path of movement of the arm when the spindle is retracted by the spring to thereby hold the spindle in a position to project the bolt, and spring actuated means which when the spindle has turned to retract the bolt resists an initial movement of the spindle to project the bolt. 80

4. In a latch of the character described, a supporting base having bolt guides, a bolt movable through the guides, a spindle mounted in the base for rotation and for longitudinal movement, said spindle having a radially extending arm, a link connecting the bolt and the arm, a spring surrounding the spindle and urging it longitudinally in one direction to carry the arm toward the base, a lug projecting from the base and with which the arm is engageable when the spindle is retracted by the spring, and a spring surrounding the bolt, and urging it to projected position. 90

5. In a latch of the character described, a bolt, a spring urging the bolt in one direction to a projected position, a spindle disposed at right angles to the bolt and operatively connected to the bolt to shift it in either direction, a rotation of the spindle in one direction shifting the bolt rearward against the action of the spring and then forward with the expansion of the spring upon a further rotation of the spindle in the same direction, and a stop limiting the forward movement of the bolt when the spindle is rotated in the said direction to thereby prevent the complete projection of the bolt, the spindle being rotatable in the opposite direction to shift the bolt rearward against the force of the spring and then permit the spring to fully project the bolt. 110

6. In a latch of the character described, a bolt, a spring urging the bolt in one direction to a projected position, a spindle disposed at right angles to the bolt and operatively connected to the bolt to shift it in 120

either direction, a rotation of the spindle in one direction shifting the bolt rearward against the action of the spring and then forward with the action of the spring upon 5 a further rotation of the spindle in the same direction, a stop limiting the forward movement of the bolt when the spindle is rotated in the said direction to thereby prevent the complete projection of the bolt, the 10 spindle being rotatable in the opposite direction to shift the bolt rearward against the force of the spring and then permit the spring to fully project the bolt, said spindle being longitudinally movable, a spring urging 15 the spindle longitudinally in one direction, and means on the spindle engaging therewith when the bolt is projected preventing the rotation of the spindle in a direction to retract the bolt until the spindle

is shifted longitudinally against the force 20 of the said coacting spring.

7. In a latch of the character described, a bolt support, a bolt slidably mounted therein, a rotatable actuating spindle mounted in the bolt support and having a radially projecting arm, a link operatively connected to the arm and to the extremity of the bolt, a spring urging the bolt to a projected position, and means coacting with the spring to 25 yieldingly hinder a rotation of the handle 30 when the bolt is in its operative or inoperative position.

In testimony whereof I hereunto affix my signature in the presence of two witnesses.

ERNEST HEINEMANN.
